A. MIELNICKI

SHACKLE LOCK

Filed Sept. 11, 1922.

A diagram of a bridge structure. It consists of a horizontal top beam supported by a central vertical post. This post is connected to two horizontal beams that extend downwards to two small rectangular piers. The entire structure is supported by a single base at the bottom.

M. Elkins
ATTORNEY

UNITED STATES PATENT OFFICE.

ALIEKSANDER MIELNICKI, OF BROOKLYN, NEW YORK.

SHACKLE LOCK.

Application filed September 11, 1922. Serial No. 587,285.

To all whom it may concern:

Be it known that I, ALIEKSANDER MIELNICKI, a citizen of Poland, residing at Brooklyn, in the county of Kings and State 5 of New York, have invented certain new and useful Improvements in Shackle Locks, of which the following is a specification.

This invention relates to improvements 10 in shackle locks and particularly to trick types in which no key of rotatable type or permutative features are used.

The main object of the invention is to provide a novel form of lock in which the bolt or securing element is entirely separable 15 from the body but may be secured positively and firmly therein by novel and simple means constituting an efficient locking device.

A further purpose is to produce a lock 20 having its bolting element engaged by merely entering the same into its body portion, but which will successfully resist attempts at separation or unlocking except by the use of means, which by courtesy may 25 be called a key although unlike any ordinary key in shape and manner of application, and which is specially provided.

Another aim is in the provision of a 30 safety lock, compact in form, strong, simple and cheap to construct.

These objects are attained by the novel construction and arrangement of parts here- 35 after described and shown in the annexed drawing, forming part of this disclosure, and in which:—

Figure 1 is a partial side, partial longitudinal sectional view of an embodiment of the invention.

Figure 2 is a bottom plan view of the 40 same.

Figure 3 is a partial side and sectional view taken in a plane at a right angle from Figure 1 and showing the bolt carrying element as raised from the body.

Figure 4 is a transverse sectional view 45 taken on line 4—4 of Figure 3.

Figure 5 is a view similar to Figure 3 but showing, like Figure 1, the bolt in an engaged position.

Figure 6 is a perspective view of the key 50 or bolt releasing device.

The main body of the lock, as shown in the drawing, consists of a hollow cylindrical casing 10 having a fixed bottom wall or 55 closure 11 above which is a chamber 12 separated by a transverse partition wall 13 from

the main chamber 14, in turn closed by a similar partition 15 from the upper open end portion 16 of the casing or body.

Extending outwardly from one side of 60 the casing, to cover a portion of the length of the chambers 12 and 14, is a web 17 used to integrally connect a solid round lug 18, containing an opening 19, preferably of 65 square cross section and open at its end directed towards the open end of the casing 10.

A cap or cover, comprised of an annular element 20, closely fitting the outer wall of the casing, circumjacent to the upper chamber 16, is formed with an integral head 21 70 and fixed rigidly at the center of the head is a bolt 22 bent to form a loop 23, the parallel portion 24 of the bolt being offset inwardly at a point below the plane of the cap head 21 and then squared to present a prong 75 element 25 suited to freely enter the opening 19 in the lug or keeper 18.

This forked shaped bolt 22 also extends through the cap, as at 26, its lower part 27 of the inner prong being squared to present 80 flat surfaces inclined convergently to the end which terminates in a plane, corresponding with the end of the bolt element 25.

Held rigidly to the faces of the element 27, by rivets 28, are flat outwardly bowed 85 springs 29, which, together with the bolt element 27, may be passed through a rectangular opening 30 in the partition 15, by the exertion of moderate force to press the spring inward, as best shown in Figure 3, 90 thereafter the springs, due to their resiliency, snapping outward, as shown in Figure 5 and, engaging below the partition 15, prevent withdrawal of the bolt 22.

In order to open the lock, by retracting 95 these several bolt elements from their connection in the casing and keeper, there is provided a square plate 31 containing an opening 32 and provided with an angularly extending handle 33 of considerable length 100 the same constituting a key.

The key is passed through a slotted opening 34 in the bottom wall 11 of the casing into the chamber 12 and then, by suitable manipulation, through the opening 35 in the 105 baffle partition 13 and then into the chamber 14 to engage the several flat springs 29 in the key plate opening 32, sliding over their outer surfaces and causing them to move inwardly until they can be passed out 110 of the opening 30 in the partition 15, this condition being readily seen in Figure 3,

whereupon the key may be readily removed.

The construction and operation will be apparent from the foregoing description and it will also be clear that minor changes 5 may be made which in no wise interfere with the spirit of the invention or scope of the appended claims.

Having thus described my invention, what I claim as new and desire to secure by Letters Patent, is:—

1. A lock comprising a cylindrical casing closed at one end and open at the other, a pair of spaced transverse partitions fixed in said casing, a cover fitting over the open 15 end of the casing, a keeper fixed parallel on said casing, a fork-shaped bolt having one prong suited to slidably engage in said keeper, the other prong being fixed in said cover to extend through the adjacent partition, resilient arms attached to the last named prong, said arms being enterable through the partition and adapted to spring 20 outward to engage its inner surface, and an angular key adapted to be inserted through 25 the closed end of said casing and adjacent partition, there being a rectangular opening

in said key adapted to engage and compress said arms to permit their withdrawal through the other partition and release said cover and bolt.

2. A lock comprising a tubular casing having a flush bottom and two spaced apertured transverse partitions constituting baffles and an apertured wall at one end, the other end being open, a keeper fixed to said casing, a bolt bent to produce parallel ends, one of which is engageable in said keeper and the other to extend into said casing, flat outturned springs fixed to the entering end of said bolt, said springs and bolt end 40 being adapted to pass through the aperture in the outermost of said partitions, a cover for said casing fixed on the entering end of said bolt the ends of said springs engaging thereafter against the inner surface of said partition, and a key enterable thru the aperture in said wall and baffle partition adapted to engage and collapse said springs 45 permitting the retraction of said bolt.

In witness whereof I have affixed my signature.

ALEX. MIELNICKI.
